JOHN FAHRNEY, OF BOONSBOROUGH, MARYLAND.

Letters Patent No. 88,150, dated March 23, 1869.

IMPROVED MOP-HEAD.

The Schedule referred to in these Letters Patent and making part of the same.

To all whom it may concern:

Be it known that I, JOHN FAHRNEY, of Boonsborough, in the county of Washington, and State of Maryland, have invented a new and improved Mop-Head; and I do hereby declare that the following is a full, clear, and exact description of the construction and operation of the same, reference being had to the accompanying drawings, making a part of this specification, in which my invention is represented by a side view.

The object of this invention is to provide for public use a neat, simple, and durable mop-head, to which the mop can be instantaneously attached without the necessity of stooping or touching it with the hands, even though the mop, at the time, be lying on the floor, or in the wash-tub.

This object is accomplished in the most simple and practical manner, by the use of a sliding, hooked rod, or bar, *a*, in connection with a bent arm, or shoulder, *b*, the mop-handle *c*, and a spring-ratchet *d*, in the manner clearly shown by the drawings.

The bar slides under the straps, or clasps *e e*, longitudinally with the handle, so as to open the hook, or close it against the brace, or shoulder *b*, as shown in the drawing.

It has a bevelled tooth, or catch *n*, on its upper end, which engages with the spring-rack, unless the latter be lifted out of its way by means of the curved part *d*, and prevents the hook from receding from the shoulder *b*, and thereby releasing the mop.

The rack itself may be a spring, or a separate spring,

s, may be employed, made of metal, rubber, or other suitable material.

In operation, if the person using the mop wishes to disengage the cloth from the mop-head, she simply lifts the ratchet *d* out of connection with the rod *a*. The latter slides out, and releases the mop at once.

The work of thus disengaging the mop and head is only of an instant, and can be performed by catching the operator's toe under the part *d*, or by catching the latter over the edge of the tub, or over any other fixture which happens to be conveniently near.

The work of uniting the mop and head is still easier, the operator having only to hook, or "fish up" the cloth from the water, or from the floor, by means of hook *a*, and then, placing the convex end of the hook against the floor, or bottom of the tub, to press the handle down against it until the end of the hook comes in contact with the shoulder *b*. This will confine the mop-cloth securely in place, and the spring-rack will then engage with the tooth *n*, and hold it there.

Having thus described my invention,

What I claim as new, and desire to secure by Letters Patent, is—

The mop-head above described, consisting of the hook *a*, shoulder *b*, handle *c*, and a spring-catch arrangement, *n d*, constructed to operate together, substantially as described, and for the purpose set forth.

JOHN FAHRNEY.
